UNITED STATES PATENT OFFICE.

JAMES R. RICKETTS, OF FORT WORTH, TEXAS, ASSIGNOR TO H. G. THOMAS
OF FORT WORTH, TEXAS.

ACETYLENE-GAS MACHINE.

No. 852,620.

Specification of Letters Patent.

Patented May 7, 1907.

Application filed May 16, 1905. Serial No. 260,688.

To all whom it may concern:

Be it known that I, JAMES R. RICKETTS, a citizen of the United States, residing at Fort Worth, in the county of Tarrant, State of Texas, have invented certain new and useful Improvements in Acetylene-Gas Machines, of which the following is a specification, reference being had therein to the accompanying drawings.

10 This invention relates to an acetylene gas machine and particularly to a structure for automatically governing the feed of carbid or gas producing material to the generator.

The invention has for an object to provide 15 an improved construction and arrangement of the coöperating parts whereby the carbid feed will be automatically controlled by the pressure of gas within the gas tank communicated from said tank by means of a float 20 and lever connection with the valve of the carbid hopper.

Another object of the invention is to provide an improved construction of the discharge valve for said hopper and of a plunger 25 carried by said valve by which the discharge neck from the hopper may be cleared of collected material, or closed to prevent the escape of gas in recharging the hopper.

Other and further objects and advantages 30 of the invention will be hereinafter set forth and the novel features thereof defined by the appended claims.

In the drawing, Figure 1 is a longitudinal section showing the assembled members of 35 the machine; Fig. 2, an enlarged vertical section of the carbid hopper; and Fig. 3, a similar view of a modified form of hopper valve.

Like letters of reference refer to like parts in the several figures of the drawing.

40 The letter A indicates the generating tank which may be of any desired construction and is preferably provided with a draw off connection A' at the normal water level therein. This tank is connected with a gas tank B by 45 means of the pipe A² which discharges at the lower portion of the gas tank and is there provided with a finely screened end A³ to break up the gas into fine bubbles so as to insure a uniform pressure within the gas tank.

50 The pipe A² within the tank is also provided with a check valve A⁴ to prevent the pressure within the tank from forcing water into said pipe, should the pressure in the generating tank fall below that of the gas tank. This

gas tank is provided with an outlet B' at its 55 normal water level and with a second outlet B² at the normal level of the gasoline or other liquid usually superposed upon the water in the tank for the purpose of washing the gas passing therethrough. 60

The gas tank is provided with the usual discharge pipe B³ connected with a filter B⁴. This filter communicates at its lower end with the pipe B³ and is provided with overlapping shelves or trays B⁵ having a fine 65 screen B⁶ extending between the same so as to intercept any solid matter floating in the gas and also to cool the gas during its passage between the plates. The gas is discharged from the filter at its upper end by means of 70 the pipe B⁷ communicating with the main, and a draw off cock B⁸ is provided for the pipe B³ below the filter.

Communicating with the lower portion of the gas tank B is a float tank C having a 75 closed lower portion, except for a pipe connection C' extending therefrom to the bottom of the gas tank and provided with a float C², of any proper dimensions to fit the diameter thereof, mounted therein and adapted to be 80 moved in accordance with the increase of the pressure within the gas tank as communicated to the body of liquid in said tank and the float tank. This float is connected with an operating lever C³ for the valve D within 85 the carbid hopper D' by means of a flexible connection C⁴. The proper level of liquid is maintained within the generating tank A and water introduced therein by means of a stand pipe A⁵ having an overflow chamber A⁶ at its 90 upper end and communicating with the lower portion of the generating tank. This tank is also provided at its bottom with a discharge neck A⁷ communicating with a draw off cock or valve A⁸. For the purpose 95 of discharging the collected lime and solid material which may fall to the bottom of the generating tank, an agitating arm E is mounted therein by means of a stem E' having a packed connection in the cap E² and 100 provided with an operating handle E³. This stem is also provided with teeth E⁴ disposed within the neck A⁷ to break up the lime or solid matter passing therethrough so that the same will be washed out in the flow of the 105 water from the tank and also to hold the agitator in proper position.

The carbid hopper D' is provided with a

cap portion D² bolted thereto in the usual manner and provided with a filling opening D³. This cap also supports a depending casing D⁴ within which the valve D is adapted 5 to slide, said casing being provided at its lower portion with a sheath D⁵ to prevent the body of material within the hopper from falling into contact with the valve. This valve is provided with a cutting edge D⁶ at its 10 lower end and is adapted to contact with the bottom of the hopper directly adjacent to the discharge neck D⁷ thereof. The valve D is carried by a tubular stem D⁸ extending upward through the body D⁹ of the casing D⁴ 15 and through a suitable packing cap D¹⁰ at the top of said body. The projected end of the tubular stem D⁸ is connected with the operating lever C³ by means of a link F arranged in any desired manner and preferably 20 pivotally connected both to the cap F' carried by the tube D⁸ and to the end of the lever at F². This lever is preferably mounted upon a suitable standard F³ carried by the upper portion of the hopper, as shown. For 25 the purpose of retaining the valve normally in a closed position a coiled tension spring F⁴ is provided for that purpose and disposed between the upper face of the valve and the body of the casing within which the valve 30 slides, so that as the valve is raised the spring is placed under tension and in its expansion firmly closes the valve and causes it to cut away and remove any material which may be resting upon its seat. The lower 35 portion of the valve D is provided with a recess within which a plunger G is disposed and preferably formed of flexible material so as to pass downward into the neck D⁷ from the hopper and clear it of any adhering material 40 such as slaked carbid, while when the hopper is opened for filling, this valve may be retained in its depressed position to prevent the escape of gas.

The plunger is normally supported within 45 the valve out of operative position by means of its stem G' extending upward through the valve and the tubular stem thereof, which stem is provided with a head G² and a tension spring G³ extending between the head 50 and the upper portion of the tubular valve stem. When it is desired to retain the plunger in the discharge neck of the hopper it may be accomplished by means of the chain or other connection G⁴ which is adapted to be 55 secured to any desired relatively fixed point, such, for instance, as a hook G⁵ carried by the lever C³.

It will be seen that when the spring G³ is 60 not compressed the plunger is inoperative and carried by the valve in its movements, while a simple depression of the head G² causes the plunger to clear the discharge neck below the valve while its spring G³ restores it to its raised position as soon as the 65 pressure is released from the head.

In the modified form of valve operating means shown in Fig. 3 the tubular stem from the valve D is omitted and the valve controlled in its downward movement by the spring F⁴ within a casing D⁴, while it is retracted by means of the plunger G which enters the recess in the valve in its upward movement and carries the valve therewith. The stem G' of this plunger is connected with the lever C³ mounted upon the standard F³ 75 by means of a link H, through which connection the plunger and valve are operated by the float C², as shown in Fig. 1. The plunger in the modified form, however, is automatically projected into the neck D⁷ by means of the tension spring H' connected at one end to the lever and at its opposite end to the top D² of the hopper. During the ordinary feeding function of the valve the plunger is adapted to pass entirely through the neck 80 and clear it of any adhering material, but when it is desired to feed the hopper it is necessary to limit the travel of the plunger so that it will stop within the neck, and for this purpose a finger H² is pivotally mounted 85 upon the lever and adapted to be swung into engagement with a stop H³ carried upon the standard F³, by which means the downward movement of the plunger under tension of the spring H' is limited. In this construction 90 of the valve it will be seen that the same is always seated by the tension of the spring which is not interfered with by the lever connections of the float and is positively opened by the upward movement of the 95 plunger. The downward movement of the plunger leaves the valve free to act, and the plunger continues independently thereof after the seating of the valve.

In the operation of the invention the gas 105 passes from the generator to the gas tank where it is washed by its passage upward through the water and gasolene and thence to the filter where it is cooled and freed from any solid substances before passage to the 110 main. The pressure in this gas tank controls the feed of carbid through the float communicating with the liquid within the gas tank, and the elevation of the float and its tank determines the pressure under which 115 the gas in the gas tank will be maintained and the consequent pressure in the main. It will be seen that the construction of valve in the carbid hopper forms means for positively closing the same under spring tension, 120 thus removing any material which may rest upon the valve seat, while the plunger carried by the valve clears the discharge neck from the hopper of any slack carbid or other adhering material after the valve is seated. When it is desired to refill the hopper it is 125 only necessary to depress this plunger into the neck and secure it in that position in order to prevent the escape of any gas when the hopper is opened. If the float tank be 130

elevated to increase the pressure of the gas tank, a similar increase of pressure may be effected in the generator by means of the stand pipe, while the solid matter at the bottom of the generator may be conveniently removed by means of the agitator there shown.

5 The provision of the float tank at a proper height above the gas tank obviates the necessity of providing a gasometer bell, as this tank not only controls the feeding valve for the generator, but also maintains a proper predetermined pressure upon the gas tank.

Having described my invention and set 15 forth its merits, what I claim and desire to secure by Letters Patent is:—

1. In a gas machine, a feed hopper having a discharge opening at its lower portion, a depending casing disposed within said hopper, a valve slidably mounted in said casing to engage a seat adjacent said opening, a tension spring disposed between said valve and the body of said casing at its upper portion, a tubular stem extending through said body and beyond said hopper, and an operating 25 lever connected to said stem.

2. In a gas machine, a feed hopper having a discharge neck at its lower portion, a valve normally held in closed position at the upper 30 end of said neck, a plunger adapted to traverse said neck and disposed within said valve and provided with a stem extending beyond said valve to permit the independent operation of the plunger when the valve is closed.

3. In a gas machine, a feed hopper having a discharge neck at its lower portion, a valve normally held in closed position, a plunger disposed within said valve and provided with 40 a stem extending beyond said valve to permit the independent operation of the plunger when the valve is closed, a spring for normally retracting said plunger within said valve, and means for retaining said plunger 45 in operative position within said neck.

4. In a gas machine, a feed hopper having a discharge opening at its lower portion, a depending casing disposed within said hopper, a valve slidably mounted in said casing 50 to engage a seat adjacent to said opening, a tension spring disposed between said valve and the body of said casing at its upper portion, a tubular stem extending through said body and beyond said hopper, a pivoted operating lever for said stem, and a link pivotally connected to said stem and operating lever.

5. In a gas machine, a feed hopper having a discharge opening at its lower portion, a 55 depending casing disposed within said hopper, a valve slidably mounted in said casing to engage a seat adjacent to said opening, a tension spring disposed between said valve and the body of said casing at its upper por-

tion, a tubular stem extending through said body and beyond said hopper, a pivoted operating lever for said stem, a link pivotally connected to said stem and operating lever, a plunger disposed within the recessed lower portion of said valve, a rod from said plunger 70 extending through the tubular stem of said valve, and a tension spring extending between a head upon said rod and the end of said stem.

6. In a gas machine, a feed hopper having a discharge opening at its lower portion, a depending casing disposed within said hopper, a valve slidably mounted in said casing to engage a seat adjacent to said opening, a tension spring disposed between said valve and the body of said casing at its upper portion, a tubular stem extending through said body and beyond said hopper, a pivoted operating lever for said stem, a link pivotally connected to said stem and operating lever, 85 a plunger disposed within the recessed lower portion of said valve, a rod from said plunger extending through the tubular stem of said valve, a tension spring extending between a head upon said rod and the end of said stem, 90 and a connection extending from said rod head to a relatively fixed point upon said lever.

7. In a gas machine, a feed hopper having a discharge opening at its lower portion, a depending casing disposed within said hopper, a valve slidably mounted in said casing to engage a seat adjacent to said opening, a tension spring disposed between said valve and the body of said casing at its upper portion, a tubular stem extending through said body and beyond said hopper, a pivoted operating lever for said stem, a link pivotally connected to said stem and operating lever, 100 a plunger disposed within the recessed lower portion of said valve, a rod from said plunger extending through the tubular stem of said valve, a tension spring extending between a head upon said rod and the end of said stem, 105 and a connection extending from said rod head to a relatively fixed point upon said lever, and a deflecting sheath carried by said casing at its lower portion.

8. In a gas machine, a feed hopper having a discharge portion, a valve seated upon said portion and provided with a recess at its lower portion, a tension spring for closing said valve, a plunger disposed within the recess at the lower portion of said valve and provided with a stem extending therethrough, and means for operating said plunger independently of the valve.

9. In a gas machine, a feed hopper having a discharge portion, a valve seated at the upper end of said discharge portion, a tension 125 spring for closing said valve, a plunger head adapted to traverse said discharge portion and disposed at the lower portion of said

valve and provided with a stem extending therethrough, and a pivoted lever for simultaneously moving said plunger and valve away from their seats.

5. 10. In a gas machine, a feed hopper having a discharge portion, a valve adapted to close said discharge portion, a plunger adapted to traverse said discharge portion after the valve is closed, and means for operating

10 said plunger in one direction independently of said valve.

In testimony whereof, I affix my signature in presence of two witnesses.
